REFRIGERATION

Charles H. MacFarland, North Canton, Ohio, assignor to The Hoover Company, North Canton, Ohio, a corporation of Ohio

Application January 13, 1938, Serial No. 184,746

28 Claims. (Cl. 62—5)

This invention relates to control mechanisms and more particularly to control mechanism particularly designed for use with refrigerating systems of the absorption type.

Heretofore, control mechanisms designed for refrigerating systems having a source of heat and a source of electrical energy to be controlled have provided separate control elements for the source of heat and the source of electrical energy. These elements must be synchronized and remain in proper synchronism throughout the entire range of adjustment thereof and during the defrosting period. Not only is initial adjustment and synchronization difficult but there are many possibilities for loss of adjustment of any or all the various control elements. Furthermore, separate safety controls and manual shut-off mechanisms must be provided.

According to the present invention there is provided a control mechanism particularly designed to control the operation of an electrical motor and a gas burner and so arranged that only a single control mechanism is required. The magnetic field of the motor is utilized to control the valve supplying gas to the gas burner whereby it is only necessary to control the supply of electrical energy to the circulating motor in order completely to control the entire machine. More specifically, a single switch element is operative to control both the gas valve and the electrical motor and perfect synchronism between the two is assured. Also, a defrosting device is provided which operates upon the switch normally controlling the gas valve and electrical motor but without in any way disturbing the calibration thereof or its particular adjusted setting.

There is provided a novel form of flame failure safety cut-off device which operates upon the normal control contact to de-energize both the electric motor and the gas burner upon flame failure and all this without in any way disturbing the calibration or adjustment of the normal control device or the defrosting control. Moreover, the safety cut-off device operates a simple visual signal means to indicate to the operator of the refrigerating system whether or not an igniting flame is present at the gas burner.

The control is so arranged that the system is automatically shut down upon failure of fuel and/or electrical energy. The safety shut down mechanism protects against any dangerous condition which might arise from failure of fuel or electrical energy but without the addition of complex controls and without affecting the adjustment of the normal control mechanism.

In addition to the normal control and the defrosting cut-off, a manual cut-off may be provided which operates upon the same mechanism but without disturbing the adjustment thereof in order that the housewife may entirely de-energize the system without disturbing any electrical or gas connections.

Other objects and advantages of the invention will become apparent as the description proceeds when taken in connection with the accompanying drawings in which:

Figure 1 is a diagrammatic representation of a continuous three-fluid absorption refrigerating system which I have elected in order to illustrate my invention.

Figure 2 is an isometric schematic diagram of the control mechanism and its connections to the electrical motor and the gas burner.

Figure 3 is a plan view of a detail of the motor.

Figure 4 is a schematic isometric view of a modified form of control mechanism.

Figure 5 is a view partly in section of a detail of Figure 4.

Referring now to the drawings in detail and first to Figure 1 thereof, there is disclosed a continuous three-fluid absorption refrigerating system comprising a boiler B, an analyzer D, a condenser C, an evaporator E, an absorber A, and a circulating fan F driven by an electrical motor M suitably connected by various conduits to form a plurality of gas and liquid circuits.

It will be understood that the system just described is diagrammatic only and that my invention is equally well applicable to other types of refrigerating systems. For example, my invention may be applied to a two-fluid absorption system utilizing an electrical motor-driven pump in the absorption solution circuit or to a continuous three-fluid absorption system of the type utilizing density differentials to produce circulation of the inert gas and a motor-driven fan to cool the absorber and the condenser.

The refrigerating system just described is suitably charged with a refrigerant such as ammonia, an absorbent such as water, and an inert pressure equalizing medium, preferably a dense gas like nitrogen.

The boiler B normally contains a solution of refrigerant in an absorbent which liberates refrigerant vapor when heated. The refrigerant vapor passes upwardly through the analyzer D in counterflow to strong absorption solution supplied thereto from a source to be described hereinafter. Absorption solution vapor which passes into the analyzer condenses therein by contact with the strong solution and the heat of con-

densation serves to generate further refrigerant vapor. The refrigerant vapor is conducted from the analyzer to the condenser through a conduit 11 which includes an air-cooled rectifier R. Any vapor of absorption solution which may escape from the analyzer is condensed in the rectifier R and returned to the analyzer.

The weak solution formed in the boiler by the generation of refrigerant vapor is conducted therefrom through a conduit 12, liquid heat exchanger 13, and conduit 14 into the upper end of the air-cooled absorber A. Weak solution flows downwardly through the absorber A in counterflow to rich pressure equalizing medium coming from the evaporator as will be described more fully hereinafter. The refrigerant vapor content of the pressure equalizing medium stream is absorbed by the solution in the absorber to form strong solution which collects in the bottom of the absorber. The strong solution is conveyed from the absorber to the upper portion of the analyzer D through a conduit 15, liquid heat exchanger 13, and a conduit 16. It is apparent that the upper end of the absorber A is at an elevation substantially higher than the liquid level normally prevailing in the boiler-analyzer system wherefor it is necessary that some means be provided to elevate the weak solution into the absorber. For this purpose, a bleed-off conduit 17 is connected between the discharge conduit 18 of the circulating fan F and the conduit 14 below the liquid level normally prevailing in the boiler-analyzer system whereby the solution is elevated into the absorber by gas lift action.

The lean pressure equalizing medium formed in the absorber exits from the upper end thereof through a conduit 19 into the suction inlet of the circulating fan F. The gas is placed under pressure in the fan F and is discharged through the conduit 18 into a gas heat exchanger 20. The lean pressure equalizing medium is discharged from the heat exchanger 20 through a conduit 21 which opens into the lower portion of the evaporator E. The evaporator E may be of any desired construction. It is shown diagrammatically herein. Preferably the evaporator will include box-cooling and freezing sections. The pressure equalizing medium flows upwardly through the evaporator E in counterflow relationship to liquid refrigerant which is supplied to the upper end thereof through a conduit 22 communicating with the bottom portion of the air-cooled condenser C. The refrigerant evaporates into the pressure equalizing medium to produce refrigeration and the resulting rich gas is returned to the gas heat exchanger through a conduit 23. The rich gas is conducted from the heat exchanger 20 into the bottom portion of the absorber A through a conduit 24 and passes upwardly therethrough in counterflow relationship to the absorption solution in a manner previously described.

The refrigerating system just described is diagrammatically illustrated and is selected for purposes of illustration only, my invention not being limited thereto but being equally well applicable to other types of refrigerating systems.

The first form of control mechanism will now be described with reference to Figures 1 to 3. The boiler B is heated by any suitable form of gas burner 31. The gas burner is supplied with fuel from a source of supply 32, a valve 33 which is mounted within the field structure of the motor M and a conduit 34. A suitable by-pass conduit 35 is provided around the valve 33 in

order to provide a small igniting flame on the burner 31; however, a separate pilot burner may be connected to the line 35, if desired. The conduit 32 is extended through openings 36 formed in ears 37 which project outwardly from one side of the field laminations 38 of the motor field 39. A small plunger 40 of magnetic material is mounted within the pipe 32 above a small orifice 41 which is placed within the pipe 32. The orifice 41 is positioned below that portion of this pipe 32 which is within the field 39 of the motor whereby upon energization of the motor field, the magnetic field thereof will elevate the pin 40 above the orifice 41 and permit gas to flow through the orifice to the burner 31. From this it will be seen that control of the energization of the motor field 39 simultaneously controls the circulation of the inert gas through the evaporator and the absorber and the supply of heat to the boiler B.

The evaporator E is preferably housed within a casing 42, though if desired, a box-cooling section of the evaporator may be positioned outside the confines of the casing. A control panel 43 rises above the front portion of the evaporator casing and forms the front wall of a control box 44.

Electrical energy is supplied to the apparatus through the wires 45 and 46. The wire 45 passes into the control box 44 and is connected to a bimetallic thermostatic switch contact element 47 which is suitably mounted upon, and insulated from, the control box 44. A complementary contact element 48 is mounted upon the front wall 43 of the casing 42 and is connected by means of a wire 49 to one terminal of the motor field 39. The other terminal of the motor field is connected by the wire 50 to the other supply line 46.

The bimetallic thermostat 47 is designed to be responsive to either box temperatures or evaporator temperatures, as may be desired; a rise in temperature causes the bimetallic element 47 to flex downwardly, as viewed in Figure 2, to close the circuit through the contact 48 and to energize the motor field 39. Energization of the motor field 39 places the circulating motor in operation and also raises the pin 40 to allow gas to flow to the burner 31. In order to adjust the temperature range of the refrigerating mechanism, an adjusting cam 51 is carried upon a shaft 52 which is mounted in any suitable manner on the control panel 43 and carries at its outer portion a control dial 53. The control dial 53 is arranged to cooperate with suitable indicia 54 whereby the operator may set the refrigerating apparatus at any desired control point. The contact 48 is constructed of spring material and normally presses downwardly against the cam; the cam adjusts the vertical position of the contact 48 against the tension thereof and thereby the width of the space between the contacts 47 and 48. This adjustment of the contact 48 determines the distance the bimetal 47 will be required to move in order to energize the circulating motor and thereby the temperature control point at which the refrigerating mechanism is placed in operation.

There is also provided a defrosting mechanism which comprises an insulating block 55 mounted on one end of an arm 56 which is pivotally mounted at 56' on an arm 57. A torsion spring 58 urges the insulating block element 55 in a counter-clockwise direction as viewed in Figure 2. The element 55 cannot rotate beyond the

position shown due to engagement between the lip 59 and an extending end portion of the supporting arm 57. The arm 57 is pivotally mounted at 60 in a bracket 61 which is suitably carried by the front wall 43 of the control box. A defrosting knob 62 is carried by a shaft 63 which extends through a suitable opening in the control panel 43. Interiorly of the control box 44, the shaft 63 is provided with a slot 64 which receives the free end of the arm 57. The end of the shaft 63 carries a collar element 65 which receives the actuating arm 66 of a toggle mechanism 67. The toggle mechanism is arranged to urge the arm 63 to the position shown or, when the knob 62 is pushed inwardly to urge the end of the shaft 63 into contact with a defrosting bimetallic thermostat 68. When the knob 62 is pushed inwardly for defrosting purposes, the arm 57 swings in a clockwise direction about the pivot 60, as viewed in Figure 2, and forces the insulating block 55 between the contacts 47 and 48 thereby preventing energization of the motor M regardless of the setting of the dial 53 and the position of the bimetallic thermostat 47. When the evaporator has reached the defrosting temperature, the bimetallic thermostat 68 bends forwardly, as viewed in Figure 2, and snaps the mechanism 67 over center into the position shown, thereby withdrawing the block 55 from engagement between the contacts 47 and 48 whereupon the apparatus returns to normal operation.

In the position shown in Figure 2, the insulating block 55 abuts the free end of a bimetallic thermostat 69 suitably carried by the side wall 35 of the casing 44. Contact between the elements 55 and 69 determines the forward limit of the knob 62 under the bias of the snap mechanism 67.

The bimetallic thermostat 69 carries a heating winding 70 which is connected by a wire 71 to the electrical supply wire 45 and by a wire 72 to the bulb 73 of a flame failure safety cut-off mechanism. The safety cut-off mechanism comprises the elongated bulb 73 which is carried by a bracket 74 in position to project the lower end thereof into the flame of the burner 31. The bulb 73 is an electrical conductor and the wire 72 extending downwardly thereinto is provided with insulation 75 except at the very bottom portion thereof which extends closely adjacent the bottom of the bulb 73. A small globule of mercury is placed within the bulb 73 to provide an electrical connection between the free end of the wire 72 and the vessel 73 except when the flame of the burner has vaporized the mercury whereupon the contact between the elements 72 and 73 is broken. Preferably the volume of the bulb 73 is very great with respect to the volume of the mercury globule and the tube is highly evacuated before sealing. These features insure rapid and complete vaporization of the mercury in response to the pilot flame. The large heat radiating area of the bulb 73 renders the response of the cut-off device to flame failure almost instantaneous as the heat of condensation of the tiny globule of mercury is very small and is dissipated from a very great area. The bulb 73 is connected by a wire 76 to the supply wire 46.

The pilot by-pass conduit 35 is provided with a valve 101 which is normally urged to closed position by a spring 102. A solenoid 103 is connected to open the valve against the bias of the spring 102. A ring 104 is provided in order that the valve 101 may be opened manually for ignition of the burner 31. One side of the solenoid

103 is connected to the wire 50 by a wire 105. The other side of the solenoid is connected to one contact of a switch 107 by a wire 108. The other contact of the switch 107 is connected to the wire 45 by a wire 109. The contacts of the switch 107 are of resilient material and are biased to open circuit position. An actuating block 110 of insulating material is mounted upon the bimetallic thermostat 69 in position to close the circuit between the contacts of the switch 107 when the thermostat is in the position shown in Figure 2.

Whenever the flame of the burner 31 is completely extinguished for any reason, the mercury contained within the tube 73 condenses and closes the circuit to the wire 71, coil 70, wire 72, bulb 73, wire 76 and line 46 whereby the thermostat 69 is heated. Heating of the thermostat 69 causes it to flex forwardly, as viewed in Figure 2, and to force the insulating block 55 between the contacts 47 and 48 and to permit the contacts of the spring 107 to separate and to de-energize the normally energized solenoid 103. The insulating block 55 does not cause the entire shaft 57 to pivot but pivots about the point 56 against the bias of the spring 58 which is weaker than the snap acting mechanism 67. This completely de-energizes the system and discontinues the supply of fuel to the burner through the orifice 41 and the spring closed valve 101.

A signalling device is provided to cooperate with the safety cut-off mechanism. The signal comprises a bell crank 77 which is pivotally mounted at 78 on an ear 79 mounted on the bottom wall of the control box 44. One arm of the bell crank carries a signal plate 80 which is positioned directly behind an opening 80a formed in the control panel 43. The signal plate 80 contains suitable indicia to indicate whether or not there is a flame carried by the burner 31. The other arm of the bell crank 77 rests against the bimetallic thermostat 69. The thermostat 69 pivots the bell crank 77 as it flexes to cause the plate 80 to indicate whether or not the gas burner is operating.

The control mechanism just described operates automatically to cycle the refrigerating apparatus between predetermined temperature limits which temperature limits may be varied at will by suitable adjustment of the control dial 53. Furthermore, the circuit breaking element 55 is operable by either or both the defrosting mechanism and the safety cut-off thermostat 69 as conditions may require. Defrosting may be accomplished at any time simply by pushing inwardly on the dial 62 without in any manner affecting the setting of the normal control dial 53.

A modification of the invention is illustrated in Figures 4 and 5. This control mechanism is designed to control a refrigerating system similar to the mechanism disclosed in Figures 1 to 3. A number of elements of this control mechanism are identical with those described in connection with Figures 1 to 3 and are given the same reference characters primed. The thermostatic contact element 48' is connected by means of a wire 81 to a contact element 82 which is formed with a depression adapted to receive a ball-headed spring pressed contact element 83. The contact element 83 is carried on the end of a plunger 80 which is received within a collar 81 of insulating material which is mounted by means of a suitable bracket 82 from the front wall of the casing 44'. A spring 83 is received within the collar 81 between the plunger 80 and

a bolt 94 so as to urge the contact 83 into engagement with the cam plate 85. The element 83 is connected by wire 84 to the field 39' of the motor M'.

The contact element 82 is mounted within a plate member 85 which is carried by a shaft 86 suitably mounted in the wall 43' and carrying a dial 87 on the free end thereof. In addition to the depression in the contact 82, the plate 85 is provided with a defrosting depression 88 and a shut-off depression 89. The plate 85 carries a depending pin 95 which is positioned within the path of movement of a bimetallic defrosting thermostat 96 which is suitably mounted in the casing 44' in position to be responsive to evaporator temperature conditions.

The normal operation of the control mechanism just described is identical with that described in connection with Figures 1 to 3; that is, the contacts 41' and 48' make and break in response to evaporator temperature changes as determined by the setting of the dial 53'. The safety cut-off 13' operates as described in connection with Figure 2 except that the insulating member 97 corresponding to the element 55 is now mounted directly upon the safety cut-off thermostat 69' and is positioned to be projected between the contacts 41' and 48' in order to de-energize the system completely upon flame failure.

The plate member 85 is made of insulating material, therefore the circuit supplying energy to the field coils 39' of the motor M' is interrupted whenever the contact element 83 is seated in the depressions 88 or 89. When the dial 87 is turned to the defrosting position, the contact 83 seats in the depression 88 and the pin 95 is in the path of movement of the thermostat 96. Therefore, when the evaporator reaches a defrosting temperature, the thermostat 96 flexes in a counter-clockwise direction, as viewed in Figure 4, against the pin 95 and rotates the plate 85 to the "on" position; that is, the contact 83 is now engaged with the contact 82 and the system returns to normal operation at the end of the defrosting period. When the dial 87 is turned to the position marked "off" on the control panel 43, the contact 83 is in the depression 89 and the pin 95 is rotated out of the path of movement of the thermostat 96 whereby the system is completely de-energized and cannot be re-energized until the dial 87 is moved to the "on" position. This provides a convenient means for de-energizing the system, for example, during a vacation period, without interfering with any of the electrical or gas connections, and for defrosting the system if for any reason it is not desired to use the semi-automatic defrosting device previously described.

The control mechanisms just described provide simple and compact structures which simultaneously regulate the supply of fuel to a gas burner and the supply of electrical energy to a circulating motor. The control mechanism is provided with a single thermostat which is readily adjustable to provide any desired temperature gradient within the refrigerating cabinet. Due to the fact that the supply of gas to the burner is regulated by a valve energized from the magnetic field of the circulating motor, perfect synchronization between the operation of the circulating motor and the boiler heater is assured and only one thermal control device need be provided for regulating the action of both these elements. Furthermore, there is provided a defrosting mechanism which will provide for a defrosting cycle of the evaporator whenever desired but without in any way af-

fecting the adjustment of the normal control mechanism. The safety control mechanism will function positively to de-energize the circulating motor and to shut off all supply of fuel to the burner upon failure of the electrical or fuel supplies or both of them.

The unique safety cut-off device is certain in operation because of the fact that it is normally open-circuited by the vaporization of an element by the gas burner, condensation of the volatile element and energization of the cut-off devices occurs immediately the flame fails. This mechanism is highly advantageous not only because of its simplicity and certainty of action but also because of the fact that there are no moving parts to get out of order, to stick, or to require precise adjustment; the characteristic of the cut-off device per se is fixed solely by the boiling temperature of the vaporizable electrical conductor bridging the contacts which govern the energization of the safety system.

While only two embodiments of the invention have been illustrated and described, it is not limited thereto but other variations and constructional forms may be used without departing from the spirit of the invention or the scope of the appended claims.

I claim:

1. Absorption refrigerating apparatus comprising a pressure equalizing medium circuit including an evaporator and an absorber, a solution circuit including a boiler and said absorber, means for supplying refrigerant vapor generated in said boiler to said evaporator in liquid form, a gas burner for heating said boiler, an electric motor driven circulator in one of said circuits, a valve controlling the supply of fuel to said burner, said valve being arranged to be controlled by said motor, means responsive to evaporator temperature conditions for controlling the energization of said motor, manually set means for de-energizing said motor, and means responsive to a defrosted condition of said evaporator for rendering said manually set means inoperative.

2. That improvement in the art of refrigeration which includes the steps of applying heat to a solution to expel refrigerant vapor, liquefying the vapor, evaporating the liquid to produce refrigeration, absorbing the vapor in solution, propelling vapor into contact with the solution under the impulse of a magnetically produced force, regulating the rate of heat supply in accordance with the intensity of the magnetically producing propelling force and regulating the intensity of the magnetically produced propelling force in accord with the demand for refrigeration.

3. That method of regulating absorption refrigerating systems of the type having a burner arranged to apply heat to a generator to produce refrigerant and an electrical motor to circulate fluids within the system which includes the steps of regulating the supply of fuel to the burner by the magnetic field of the motor and controlling the energization of said magnetic field in response to demands for refrigeration.

4. Absorption refrigerating apparatus including a generator, an evaporator, heating means for said generator, power-driven means for circulating a pressure equalizing medium through said evaporator, fuel supply means for said heating means, a valve in said fuel supply means positioned to be opened by the magnetic field of said motor, and means responsive to demands for re-

frigeration for controlling the energization of said magnetic field.

5. Absorption refrigerating apparatus including a generator, an evaporator, heating means for said generator, power-driven means for circulating a pressure equalizing medium through said evaporator, fuel supply means for said heating means, a valve in said fuel supply means positioned to be opened by the magnetic field of said motor, means responsive to demands for refrigeration for controlling the energization of said magnetic field, means for adjusting the temperature setting of said last mentioned means, manually set defrosting means for rendering said temperature responsive means inoperative, and means responsive to a defrosting condition of said evaporator for rendering said defrosting means inoperative.

6. Refrigerating apparatus comprising an evaporator, a boiler, a gas burner for heating the boiler, an electric motor-driven fan for circulating fluid through said evaporator, a valve operated by the magnetic field of said motor for controlling said burner, means independent of said valve for supplying gas to maintain an igniting flame at said burner, a solenoid valve controlling said igniting flame supply means, a thermostatic switch for controlling the energization of said motor in response to refrigeration demand, means for de-energizing said motor for defrosting purposes, means for re-energizing said motor when said evaporator has defrosted, a bulb positioned to be heated by the igniting flame at said burner, an electrical conductor in said bulb which will be vaporized by flame at said burner, electrical connections to said bulb arranged to be open circuited when said electrical conductor is vaporized, and means energized by said electrical conductor in response to flame failure at said burner for de-energizing said solenoid valve and for opening said thermostatic switch to de-energize said motor independently of the position of said switch and said defrosting means.

7. Refrigerating apparatus including a heating gas burner, an electrically energized fluid circulator, means responsive to refrigeration demand for controlling the energization of said circulator, means actuated by said circulator for controlling the fuel supply to said burner, means providing an igniting flame at said burner, and means operative to de-energize said circulator upon failure of fuel supply to said burner, or failure of said igniting flame.

8. Refrigerating control mechanism comprising a temperature responsive switch mechanism, means for varying the temperature at which said switch is operated, defrosting mechanism for rendering said switch ineffective, and flame failure responsive mechanism for opening said switch independently of said defrosting mechanism and the operating temperatures thereof.

9. Control mechanism comprising a thermostatically operated switch, means for regulating the operating characteristics of said switch, a three position switch connected in series with said first mentioned switch, said three position switch having a closed circuit position and two open circuit positions, a defrosting thermostat for returning said switch to closed circuit position from one open circuit position, a flame failure responsive means, a pilot flame control switch, and means energized by said flame failure responsive means for opening said pilot flame and thermostatically operated switches independently of

said regulating means and said three position switch.

10. Control mechanism comprising a thermostatically operated switch, means for regulating the operating characteristics of said switch, an insulating body positioned to be inserted between the contacts of said switch, a defrosting mechanism including manually set means for inserting said body between said contacts and thermostatic means for withdrawing said body from said contacts, a flame failure responsive means, an ignition flame control switch, and means energized by said flame failure responsive means for opening said ignition flame control switch and for moving said body between said contacts independently of said regulating means and said defrosting mechanism.

11. Refrigerating control mechanism comprising a thermostatic control device, a manually set control device, said manually set control device being settable in a plurality of positions in which said thermostatic control device is rendered ineffective to perform its normal functions and another position in which said thermostatic control device is unaffected thereby, and means responsive to an abnormal temperature condition for shifting said manually set control device from one of said plurality of positions to another position.

12. Refrigerator control mechanism comprising a pair of switch contacts, means urging one of said contacts to open circuit position, manually set means for adjusting the position of said contact which is urged to open position, temperature responsive means for actuating the other of said contacts to open and closed circuit positions, circuit interrupting means adapted to be placed between said contacts, and means for moving said circuit interrupting means to and from position between said contacts.

13. Refrigerator control mechanism comprising a pair of switch contacts, means urging one of said contacts to open circuit position, manually set means for adjusting the position of said contact which is urged to open position, temperature responsive means for actuating the other of said contacts to open and closed circuit positions, circuit interrupting means adapted to be inserted between said contacts, manually set means for placing said circuit interrupting means between said contacts, and temperature responsive means for withdrawing said circuit interrupting means from position between said contacts.

14. Refrigerator control mechanism comprising a pair of switch contacts, means urging one of said contacts to open circuit position, manually set means for adjusting the position of said contact which is urged to open position, temperature responsive means for actuating the other of said contacts to open and closed circuit positions, manually set means for interrupting the flow of electrical energy through said contacts in a plurality of positions and for permitting such energy flow in another position, and temperature responsive means for returning said manually set means from one of said plurality of positions to said another position.

15. In combination, a gas burner, an electric motor, said motor having a field piece provided with an opening therethrough, a magnetic valve element in said opening, means including said opening for supplying gas to said burner, temperature responsive means for controlling the energization of said motor, means for providing a pilot flame at said burner independently of

said valve, a bulb positioned to be heated by said pilot flame, a body of mercury in said bulb, means forming an electric circuit including said body of mercury, means for de-energizing said motor and for discontinuing the supply of fuel to said pilot burner, said last mentioned means being energized by said electric circuit, the arrangement being such that said pilot flame vaporizes said mercury and opens said electric circuit.

16. A flame responsive device comprising a sealed evacuated vessel constructed from electrical conducting material, a body of mercury in said vessel, an electrical conductor having a portion thereof in said mercury and insulated from said vessel, and another electrical connection to said vessel whereby vaporization of the mercury breaks the electrical conducting path between said electrical conductor and said vessel.

17. In combination with an absorption refrigerating system of the type including an inert gas circuit, a motor driven inert gas circulator, a fuel burner for applying heat to a suitable portion of the system, means providing a fuel supply for a pilot flame for said burner, means actuated by the magnetic field of said motor for governing the supply of fuel to said burner, refrigeration demand responsive means for regulating the energization of said motor, and flame failure responsive means for de-energizing said motor and said pilot flame fuel supply means.

18. In combination with an absorption refrigerating system of the type including an inert gas circuit, a motor driven inert gas circulator, a fuel burner for applying heat to a suitable portion of the system, means actuated by the magnetic field of said motor for governing the supply of fuel to said burner, and refrigeration demand responsive means for regulating the energization of said motor.

19. In combination with an absorption refrigerating system of the type including an inert gas circuit, a motor driven inert gas circulator, a fuel burner for applying heat to a suitable portion of the system, means actuated by the magnetic field of said motor for governing the supply of fuel to said burner, refrigeration demand responsive means for regulating the energization of said motor, manually operable means for de-energizing said motor, and a defrosting release thermostat for operating said manually operable means to a position in which said motor is energized.

20. In combination with an absorption refrigerating system of the type including an inert gas circuit, a motor driven inert gas circulator, a fuel burner for applying heat to a suitable portion of the system, means actuated by the magnetic field of said motor for governing the supply of fuel to said burner, refrigeration demand responsive means for regulating the energization of said motor, manually operable means movable to a plurality of positions in which said motor is de-energized, and a defrosting release thermostat operable to move said manually operable means from one one of said plurality of positions to another position in which said motor is energized.

21. Control mechanism for a fuel burner comprising a main fuel supply control means, a pilot flame fuel supply control means, a temperature control thermostat, and a safety cut-off device positioned in heat transfer relationship with said burner comprising an element adapted to change phase in response to the establishing or extinguishing of flame adjacent said burner to open or close an electrical circuit, and an electrical circuit including all of said elements and ar-

ranged to operate on said fuel supply means to discontinue all fuel supply in response to failure of flame at said burner.

22. Absorption refrigerating apparatus including a motor driven fluid circulator, a fuel burner, means actuated by said motor for controlling the supply of fuel to said burner, a vessel positioned to be affected by the condition of said burner, a substance in said vessel adapted to condense and vaporize in response to changes in the condition of said burner, and an electrical circuit including said motor and said substance whereby said fluid circulator and said burner are co-ordinately controlled by the condition of said burner.

19 23. In combination a three-fluid absorption refrigerating system including a motor driven inert gas circulator and a refrigerant generator operable by heat, a fuel burner for heating said generator means for supply fuel to said burner, means operated by said motor for controlling the supply of fuel to said burner, means providing a pilot flame in igniting relationship to said burner, and means including an electric circuit including a vaporizable element therein for controlling said motor, the arrangement being such that condensation of said vaporizable element energizes said motor to operate said fuel supply control mechanism to open position.

24. Control mechanism comprising a fuel burner, a valve for controlling the supply of fuel to said burner, an electrical control circuit including a valve actuator, a temperature responsive regulator and a cut-off device, said cut-off device comprising an element positioned adjacent said burner to be affected by the heat thereof and adapted to change phase when the flame is extinguished to close an electrical circuit operative when energized to de-energize said valve actuator to discontinue the supply of fuel to said burner.

30 25. Control mechanism for a fuel burner comprising an electrical circuit including means for governing the supply of fuel to said burner and a flame failure cutoff comprising an element adapted to change phase and electrical conductivity in response to failure of flame on said burner whereby said governing means discontinues the supply of fuel to said burner, said cut-off including a wall portion to be subjected to the burner flame which is heat conductive.

35 26. In combination a gas burner, an electric motor, said motor having a field piece provided with an opening therethrough, a magnetic valve element in said opening, and means including said opening and said magnetic valve element for supplying gas to said burner.

40 27. A flame responsive control device comprising an electrical circuit including a casing element to be subjected to a flame constructed of material which is heat conductive and electrically conductive, a material within said casing which changes phase in response to changes in the thermal condition thereof and which is electrically conducting in one phase and electrically non-conducting in another phase, means providing for a first electrical connection for said circuit to said casing and a second electrical connection to said material, and means providing an insulated seal for said second connection through the wall of said casing whereby said circuit is open or closed in accordance with the phase of said material.

45 28. In combination with a burner and a fuel supply means therefor, a safety control mechanism for said burner comprising a safety control

electric circuit including means arranged when said circuit is energized to discontinue the supply of fuel to said burner by said fuel supply means and a flame responsive device positioned to be heated by said burner and arranged to maintain said circuit open when heated and to close said circuit in response to failure of flame at said

burner, said device comprising an electrically conductive casing forming a part of said control circuit, and a vaporizable material in said casing and included in said electric circuit which is 5 non-conductive when vaporized by the heat of said burner.

CHARLES H. MACFARLAND.
